UNITED STATES PATENT OFFICE.

WILLIAM JOHNSON, OF LEEDS, ENGLAND, ASSIGNOR OF ONE-HALF TO THE SOMERSET AND JOHNSONBURG MANUFACTURING COMPANY, OF SOMERSET, MASSACHUSETTS.

CONTINUOUS BRICK-KILN.

SPECIFICATION forming part of Letters Patent No. 472,926, dated April 12, 1892.

Application filed September 3, 1891. Serial No. 404,656. (No model.)

To all whom it may concern:

Be it known that I, WILLIAM JOHNSON, a subject of the Queen of Great Britain, residing at Leeds, in the county of York, England, 5 have invented certain new and useful Improvements in Continuous Kilns; and I do hereby declare the following to be a full, clear, and exact description of the invention, such as will enable others skilled in the art to which 10 it appertains to make and use the same.

This invention relates to certain new and useful improvements in kilns for burning bricks, tiles, fire-bricks, and the like of that 15 class known as "continuous kilns;" and it has for its objects, among others, to provide a kiln of this class of peculiar construction whereby the combustible properties of the fuel are fully extracted and the utmost possible heating power is obtained, nothing being allowed 20 to escape or pass away to the chimney beyond a slightly-heated vapor.

It has for a further object to so construct the kiln that the process of firing, charging, and discharging may be made continuous, 25 thereby avoiding the necessity of having to restart the firing at the beginning end of the kiln each time the whole length is completed.

I provide a hot-air flue surrounding the arched tunnels of the kiln. Hot-air flues are not new 30 in this connection; but heretofore they have been arranged beneath the tunnel or heating-chamber and communicated therewith through openings in the doorways of the different sections of the kilns. I arrange my

35 hot-air flue above or near the top of the tunnels and provide communication between this flue and each chamber by means of inlets, each of which is provided with a damper. By this means the steaming of the goods is effected by the wasting heat from the burned off and cooling section or sections. The dampers in the inlets communicating with the burned-off section or sections are opened, and 40 also those appertaining to the newly-charged

45 section. This permits the hot air to be conveyed along the hot-air flue from the burned-off section or sections and to be discharged into the green or newly-charged section, all other inlets being closed. The moisture is 50 thoroughly expelled and the goods raised to a

high heat. I provide a main central flue communicating with the chimney, and each chamber or section of the tunnel is connected to said main central flue by means of by-flues, which communicate with the chambers or sections by means of recesses situated in the outer wall near each wicket and provided each with a damper adapted to be actuated in any suitable manner, preferably from the top of the kiln. I economize space and provide a compact and efficient kiln.

Other objects and advantages of the invention will hereinafter appear, and the novel features thereof will be specifically defined in the appended claims.

The invention is clearly illustrated in the accompanying drawings, which, with the letters of reference marked thereon, form a part of this specification, and in which—

Figure 1 is a vertical longitudinal central 70 section through a kiln constructed in accordance with my invention. Fig. 2 is a central vertical cross-section through the same. Fig. 3 is a section plan on the ground-line. Fig. 4 is a plan view of the top of the kiln, looking 75 from the line $\alpha\alpha$ downward, Fig. 1. Fig. 5 is a side elevation, and Fig. 6 a detail view, of the damper.

Like letters of reference indicate like parts throughout the several views in which they 80 occur.

In the drawings I have shown what I consider the best form in which my invention may be embodied; but I wish it understood that I do not intend to restrict myself to any 85 particular shape or size of kiln, as the same type of kiln may be built of different shapes and sizes and may be employed for different purposes than for burning bricks, and other classes of goods may be burned therein which 90 require the same or similar treatment or mode of operation. The form shown is the one preferred.

Referring now to the details of the drawings by letter, A designates the building, which in 95 this instance is shown as rectangular, inclosing two arched tunnels A', running substantially parallel to each other and joined or connected together by the semicircular ends A², the whole forming one continuous tunnel, as 100

seen best in Fig. 3. This tunnel is divided into imaginary chambers or sections, each chamber being furnished with one or more by-flues D, connected to the main longitudinal flue E, which is arranged to one side of the central longitudinal division-wall a, between the two side tunnels, as seen in Fig. 2, and preferably beneath the said tunnels, as seen in said Fig. 2. This central main flue communicates with the chimney B, as shown in Fig. 3. This chimney may be situated either inside or outside of the building, as may be preferred. The flues D communicate with each chamber or section by means of the recesses or offsets F, as seen best in Figs. 2 and 3, which are formed in the outer walls near each wicket or doorway C, which are provided in the outer walls for the purposes of communication with the interior of each chamber or section, there being a doorway for each chamber or section, as seen in Fig. 3. These flues D extend angularly, as shown in Fig. 3, so as to give the maximum amount of heating-surface, and the flues upon opposite sides of the kiln alternate, as indicated in Fig. 3—that is, the points of connection of the said flues upon one side with the main central flue are opposite the space between the flues upon the other side, so that the flues will not interfere 30 the one with the other, and but one-half the length of the main central flue is left between the two adjacent flue connections that there would be if the flues were not thus alternately arranged. Better draft and more uniform heating is thus provided.

The flues D are each provided with a damper J, designed to be actuated from the top of the kiln in any suitable manner, as by the rods G. (See Figs. 1 and 6.)

For the purpose of firing the kiln, the top of the kiln is provided with a number of firing openings or sockets H, which communicate with each chamber or section, and should be provided with removable covers or caps.

N is a hot-air flue extending around the whole length of the outer wall of the kiln and at a point above or near the top of the tunnel, as seen in Figs. 1 and 2. It communicates with each chamber or section by means of the passages R, each passage being provided with a damper S, operated from the top of the kiln in any suitable manner, as by the rods M.

Any preferred form of damper may be used for the hot-air flue and by-flues D. For the latter I prefer that shown in Fig. 6, and in which the damper J has a surrounding-flange j to embrace the upwardly-extending flange j' of the frame K, which is formed with horizontal flange k, by which it is held in position, the depending flange of the damper forming a tight joint around the upwardly-extending flange of the frame and preventing escape of heat. The damper is formed with a central boss k', extending above and below its body portion and through which the damper-rod passes, being provided with jam-nuts or other provisions l for holding the rod in position.

In operating the kiln two chambers or sections are charged with bricks, tiles, or other articles or goods conveniently set to allow a free draft to pass through them, provision being made, also, for firing through the openings H in the roof of the kiln.

On reference to Fig. 4, O designates a temporary wall or partition built across the tunnel of the kiln about four feet from the face of the bricks or tiles or other goods with which the two sections or chambers are charged and having two or more firing-holes. At the terminating end of the two chambers or sections a temporary wall or partition P is built with openings through its bottom. This partition is made thoroughly air-tight, so as to confine the draft within the two chambers or sections in which the firing is started. The charged sections are then ready for firing, and the fires are started from the temporary firing-holes in the partition O in front of the first section and continued until the heat inside the two sections is raised to about the required temperature, when the fire-holes in the partition are closed and the firing continued through the openings H in the roof of the kiln.

Any suitable fuel may be employed; but I prefer very small slack, which is fed into the openings in any suitable manner, as with a small scoop, a very small quantity being scattered through the holes at periods of about a quarter of an hour. The slack, on being dropped into the heated mass of bricks, with which it comes in contact, is at once formed into a gas and by mixing with the hot air passing from behind ignites, filling the kiln with a bright flame, by which means the process of firing is continued.

During the firing of the first two sections the filling of the adjoining sections or chambers is proceeded with, and when completed is made air-tight in the same manner as before described, and the openings at the bottom of the preceding partition P are cleared and the dampers in the newly-prepared section are now raised by means of their rods G and the heat from the previous sections is drawn through the goods in the recently-attached section, which becomes thoroughly heated by the gases which have been admitted, and has its heat kept up or sustained by the process of firing through the holes in the roof, as before described. By this method the process of firing is continued in the various sections, and if the tunnel forming the kiln is made endless, as shown, the burning is made continuous and may therefore be continued for any desired length of time.

By means of the hot-air flue N the heat can be conveyed from any one or more chambers into any other one or more chambers situated in any part of the kiln, and thereby the moisture or steam is thoroughly expelled and the goods subjected to a great heat.

It is deemed important that the hot-air flue be arranged near the top of the kiln, where it will take the heat from the top thereof, which

is of course greater than at the bottom of the kiln and which will more readily find its way into the flue than were it located beneath the tunnel as heretofore.

5 Modifications in detail may be resorted to without departing from the spirit of the invention or sacrificing any of its advantages.

What I claim as new is—

1. The combination, with a continuous kiln consisting of parallel tunnels comprising a series of chambers and a hot-air flue arranged in the outer wall of said kiln, of the main central flue, the by-flues extending from either side of said main flue and terminating in recesses formed in the outer wall of each chamber for conveying off the products of combustion, and dampers for closing said by-flues, as set forth.
2. The combination, with a continuous kiln consisting of parallel and communicating tunnels comprising a series of chambers, and a hot-air flue arranged in the outer wall of said kiln, and the main central flue, of the by-flues conveying off the products of combustion.

tion extending across the tunnel of the kiln 25 from either side of said central flue and arranged in an inclined direction relatively to the main flue, recesses formed in the outer side walls, and vertically-operated dampers 30 for closing said by-flues, as and for the purpose specified.

3. In a kiln, the combination, with the continuous parallel tunnels, the central flue, the side recesses formed in the walls of said kiln, and flues connecting said recesses and the 35 main flue from each side of the main flue, of the surrounding hot-air flue located in the wall of the kiln near its top and having lateral connections with the chambers of the kiln, and vertically-operated dampers for said 40 lateral connections, as set forth.

In testimony whereof I affix my signature in presence of two witnesses.

WILLIAM JOHNSON.
